UNITED STATES PATENT OFFICE.

LEWIS WILLIAM EVANS, OF PITTSFIELD, MASSACHUSETTS, ASSIGNOR TO GENERAL ELECTRIC COMPANY, A CORPORATION OF NEW YORK.

PLUG PULLER.

Application filed December 7, 1923. Serial No. 679,270.

The present invention relates more especially to devices for the safe operation of primary cutouts and commonly called plug pullers.

5 The potential at which electric current is distributed in cities and towns is generally regulated by municipal ordinance and varies from twenty-three hundred to forty-six hundred volts, and in order that it may be safely 10 introduced into buildings, it is stepped down by transformers to one hundred and twenty-five or two hundred and fifty volts. In order that the transformers may be readily disconnected from the high potential circuit, primary cutouts are provided 15 and these primary cutouts are generally in the form shown in the Sargent Patent No. 1,014,854, January 16, 1912, and adapted to be manually opened by pulling out the plug 20 thereof.

On account of the possibility of drawing a dangerous arc, especially in rainy weather, in the breaking of the high voltage primary circuit, it has been the practice to employ 25 a plug puller mounted at the end of a wooden pole so that the operator may remain out of the range of any electric arc that may be formed while the breaking of the circuit takes place.

30 The object of my invention is the provision of an improved plug puller which may be engaged with a plug with facility, which will permit ample stress to be applied to detach the plug without injury thereto, which will prevent accidental disengagement of the freed plug therefrom, and which after restoration of the plug to 35 its operative position may be detached with facility therefrom.

40 One embodiment of the invention is shown in the accompanying drawing in which Fig. 1 is a front elevation of a primary cutout with my plug puller in engagement with the plug thereof, and Fig. 2 is a perspective view of the plug puller.

45 The box and the plug portions 1 and 2 of primary cutouts are customarily made of porcelain and the plug is provided with an operating handle or knob 3 and a transverse flange 4.

50 My plug puller 5 consists of a metal head 6 having at its outer end a transverse portion 7 provided with a key-hole slot 8 and its inner end 9 spaced therefrom and formed 55 with a socket for mounting upon the end

of a wooden pole 10 to which it is attached by pins or rivets 11.

The larger portion 12 of the key-hole slot 8 is adapted to permit the plug knob 3 to be freely entered, while the narrow portion 13 of the slot will receive only the neck 14 of the knob, and it is so positioned that when the plug is in engagement therewith it will be concentric with the pole 10.

In order yieldingly to retain the engagement between the puller and the plug knob, the former is provided with a leaf spring 15 is attached by bolts 16 to the inner head end 9 and extending diagonally outward beneath the keyhole slot 8 so as to present an inclined surface to the plug knob 3 and tending to press the latter towards the narrow portion 13 of the slot. The spring 15 also operates to cause the plug, when freed from its box, to assume an erect position in alignment with the pole 10 and thus facilitate its restoration to operative position in the box 1. After replacement of the plug in its operative position, the puller 5 may be disengaged therefrom by transverse pressure applied to the pole 10 to overcome the resistance of the leaf spring 15, and when the knob 3 clears the contracted slot portion 13 the spring will tend to eject it through the larger slot portion 12.

While I have shown and described the best embodiment of the invention known to me, I do not desire to be restricted thereto.

What I claim as new and desire to secure by Letters Patent of the United States, is:—

1. A plug puller having an outer transverse portion provided with a keyhole slot adapted to engage the end of the plug and an inner portion spaced from said outer portion and provided with means for the attachment of a pole therewith in alignment with the contracted portion of said keyhole slot.

2. A plug puller having an outer transverse portion provided with a keyhole slot adapted to engage the end of the plug, and an inner portion spaced from said outer portion and having provision for attachment to the end of a pole, and a leaf spring disposed between said outer and inner portions and extending diagonally outward toward said outer portion.

In witness whereof, I have hereunto set my hand this 4th day of Dec., 1923.

LEWIS WILLIAM EVANS.
